UNITED STATES PATENT OFFICE.

AUGUST NEYER, OF SAN FRANCISCO, CALIFORNIA.

HAIR-WAVING DEVICE.

1,299,008.

Specification of Letters Patent.

Patented Apr. 1, 1919.

Application filed August 13, 1918. Serial No. 249,618.

To all whom it may concern:

Be it known that I, AUGUST NEYER, a citizen of Switzerland, residing at the city and county of San Francisco and State of California, have invented new and useful Improvements in Hair-Waving Devices, of which the following is a specification.

This invention relates to a hair waving device, and more particularly to a device for 10 forming a series of waves better known to the trade as Marcel waves.

One of the objects of the present invention is to provide a simple, substantial, easily operated device of the character described 15 by which the hair may be quickly, and, practically speaking, permanently waved.

Another object of the invention is to provide means for electrically heating the waving device, and also of applying the heat 20 in such a manner that the high and low points of the hair waves are subjected to more heat than the remainder of the hair.

Another object of the invention is to provide a pair of housings, one adapted to telescope within the other, and a novel frame structure within each housing for the support of the heating elements.

Further objects will hereinafter appear.

The invention consists of the parts and 30 the construction and combination of parts as hereinafter more fully described and claimed, having reference to the accompanying drawings in which—

Figure 1 is a central, vertical, longitudinal 35 section through the hair waver.

Fig. 2 is a plan view of one of the sections comprising the hair waver.

Referring to the drawings in detail, A and B indicate a pair of box-shaped casings 40 which are adapted to telescope one into the other as shown in Fig. 1. Secured to the casing B are a plurality of heating elements such as shown at 2, and similarly secured to the casing A are a plurality of heating elements 3. Each heating element is inclosed in a metallic shield or form as shown at 4, and the forms are in turn secured in frames such as shown at 5 and 6, the frame 6 being secured in the casing A, and the frame 5 in 45 the casing B. The forms may be secured in the frames in any suitable manner, and the heating elements 3 and 4 are, of course, secured within the forms. Any suitable form of elements may be employed, but it is 50

essential that they be insulated from the 55 forms as shown at 7.

By referring to Fig. 1 it will be seen that when the casings are brought together or telescoped one into the other, that the heating elements 2 are staggered with relation 60 to the elements 3; the hair when placed between the elements will, therefore, assume a wave-like formation such as shown.

In actual operation current may be supplied from an ordinary incandescent lamp 65 circuit through the wires 8 and 9 as shown. The hair to be waved or treated is combed out and is preferably dipped in a solution to render the waving effect more or less permanent. After dipping the hair in the solution desired, I find it practical to wrap the hair in tissue paper, and then to place it lengthwise in the casing A. Casing B is then telescoped into the casing A, and as 70 the elements 2 will interpose themselves between the elements 3, it can readily be seen that the hair placed between the elements will assume the wave-like formation shown.

The hair is now permitted to remain from 10 to 15 minutes and subjected to the heat of the elements during this time period. It is, therefore, not only thoroughly dried, but 75 also baked to such an extent that practically speaking a permanent wave formation is obtained. The casing sections may now be separated and the paper wrapping removed, thus leaving the casing in readiness for the insertion of more hair. The solution employed in connection with the hair for the 80 purpose of rendering the wave-like formation more or less permanent does not form

any part of the present invention, and I similarly wish it understood that the materials and finish of the several parts employed may be such as the experience and judgment of the manufacturer may dictate.

Having thus described my invention, what I claim and desire to secure by Letters Patent is:

1. A hair waving device comprising opposed telescoping members, forms within said members for the reception of the hair, and means for heating the forms.

2. A hair waving device comprising opposed telescoping casing members, a plurality of forms secured in each casing member and staggered with relation to each other, and means for heating the forms,

3. A hair waving device comprising opposed telescoping casing members, a plurality of forms secured in each casing member and staggered with relation to each other, and an electrically operated element with each form and insulated therefrom.
4. A hair waving device comprising a pair of casing members one adapted to be telescoped within the other, an opening formed in each end of each casing member, a frame secured within the casing, a plurality of interspaced elliptical-shaped forms secured

in each frame, said forms adapted to alternately pass between each other when the casing sections are telescoped, and an electric heating element within each form and insulated therefrom. 15

In testimony whereof I have hereunto set my hand in the presence of two subscribing witnesses.

AUGUST NEYER.

Witnesses:
